J. BLACKBURN

EXPANDING SCREW ANCHOR

Filed Feb. 9, 1922

Inventor:
Jasper Blackburn.

By Edward E. Longman
Attorney

UNITED STATES PATENT OFFICE.

JASPER BLACKBURN, OF ST. LOUIS, MISSOURI.

EXPANDING SCREW ANCHOR.

Application filed February 9, 1922. Serial No. 535,213.

To all whom it may concern:

Be it known that I, JASPER BLACKBURN, a citizen of the United States, and resident of the city of St. Louis and State of Missouri, have invented certain new and useful Improvements in Expanding Screw Anchors, of which the following is a specification containing a full, clear, and exact description, reference being had to the accompanying drawings, forming a part hereof.

My invention relates to improvements in expanding screw anchors, and has for its primary object a screw anchor carrying expanding plates, which anchor is adapted to be inserted in the ground by a twisting or boring movement, and when the proper depth has been reached, the plates are expanded into the solid ground so as to prevent the withdrawal of the anchor.

A further object is to construct an expanding screw anchor in which the expanding plates are pushed into the ground surrounding the bore by the same wrench which is used to drive the anchor in the ground.

In the drawings,

Fig. 1 is a side elevation of my device with portions thereof broken away, and portions in section.

Fig. 2 a cross section taken on the line 2—2 of Fig. 1.

Fig. 3 a cross section taken on the line 3—3 of Fig. 1, showing the plates expanded.

Fig. 4 a bottom plan view of the eye with the wrench shown in dotted lines.

In the construction of my device I employ a boring member having a flat plate 5 which has formed integral with its lower portion a boss 6, this boss tapering to a point as indicated by the numeral 7. A portion of the plate 5 is cut away as indicated by the numeral 8. The boss 6 is provided with a helix 9, which loosens the ground and conveys it upward to the opening 8, thus allowing the plate 5 to sink downward

into the ground. The boss 6 is provided with a screw-threaded opening 10, which opens into a bore 11. This bore is cored in and eliminates the use of a bottoming tap when forming the screw threaded bore

10. Extending through the wall of the boss 6 and communicating with the opening 11 is an opening 12, through which a tool can be inserted for mutilating the threads 13 on the rod 14. The upper end of the rod is screw threaded, as indicated at

15. Pivots secured to the plate 5 by means of rivets or the like 16, are expanding plates 17. These plates are so shaped as to cover substantially the entire plate 5, with the exception of the opening 8. The outer edges of the plates 17 are beveled as at 18, to permit them being readily forced into the solid earth which surrounds the bore. The upper face of the plate 5 is provided with an integral rib 19 which acts as a stop for the plates 17 when closed. The plate 5 is also provided with a rib 20. This rib is a part of the helix, and is for the purpose of directing the earth carried upward to the plates 17. Formed integral with the plates 17 and projecting upwardly therefrom, are bosses 21. These bosses are provided with a central opening 22, and an undercut portion 23, which are for the purpose of permitting the insertion of the expanding member 24. This expanding member consists of a cylindrical portion with which are integrally formed cam arms 25, the upper portion having a rectangular portion 26. The expanding member is provided with a central bore 27, through which the rod 14 passes, and the expanding member is held in position on the rod by means of a collar 28. The rectangular portion 26 is of substantially the same size as the upper portion of the bosses 21, which when the plates are collapsed form substantially a rectangular projection, and over these two rectangular portions is placed a wrench 29. This wrench is turned by means of a handle 30 which is adjustably mounted thereon. When screwing the anchor into the ground, the eye 31 is placed in position on the rod 14, and the cylindrical projection 32 formed on the underside of the eye enters the wrench 29, and steadies the upper portion thereof.

The operation of my device is as follows:

After the device together with the wrench has been assembled, as shown in Fig. 1, the plate 5 is turned, and by means of the helix 9 is gradually drawn into the ground. When a sufficient depth has been reached, the eye 31 is screwed upward so that the wrench can be raised sufficiently that when it is turned it will only operate the expanding member 24 which is loosely mounted on the rod 14. When the wrench has been raised sufficiently high, it is turned again by means of the handle. At this period the cam arms 25 come in contact with the re-

cesses 23 and force the plates apart as shown in Fig. 3. This forces the plates outward into the solid ground around the bore formed in driving the anchor down, and 5 prevents it from pulling up before the loose ground of the bore has had a chance to settle. The eye 31 is then removed entirely from the rod 14, and the wrench 29 and handle 30 removed from the rod, after which 10 the eye is again replaced for the purpose of securing the guy wire or rope thereto.

By the use of my device no twisting of the anchor rod 14 is necessary, and the same can be securely fastened within the plate 5, 15 and with the elimination of any twisting of the rod 14, there will consequently be no danger of fracturing the rod either wholly or partially, and thus weaken it.

Having fully described my invention, 20 what I claim is:

1. An expanding screw anchor comprising a boring member in the form of a disc, a pointed projection formed integral with the underside of said disc, a helix encircling 25 said pointed projection and integral therewith and with said disc, an opening formed in said disc adjacent the upper portion of said helix, expanding plates pivotally secured to the upper surface of said disc, a 30 rod secured in said disc and projection, an expanding member loosely located on said rod, means for preventing lateral movement of said expanding member, undercut 35 projections integrally formed with the expanding plates, said under cut projections surrounding the lower portion of the expanding member, a rectangular portion formed integral with the expanding member and above the under cut projections, and 40 a wrench for inserting said anchor into the ground and for rotating the expanding member for forcing the expanding blades outward when the anchor is sunk into the ground.
2. An expanding screw anchor comprising a boring member in the form of a disc, a pointed projection formed integral with the underside of said disc, a helix encircling 45 said pointed projection and integral therewith and with said disc, an opening formed in said disc adjacent the upper portion of said helix, expanding plates pivotally se-

cured to the upper surface of said disc, a rod secured in said disc and projection, an expanding member loosely located on said rod, means for preventing lateral movement 55 of said expanding member, undercut projections integrally formed with the expanding plates, said under cut projections surrounding the lower portion of the expanding member, a rectangular portion formed integral with the expanding member and above the under cut projections, a wrench for inserting said anchor into the ground and for rotating the expanding member 60 for forcing the expanding blades outward when the anchor is sunk into the ground, and an eye having a cylindrical projection screw seated on the upper portion of the rod, said cylindrical projection adapted to 65 steady the upper end of the wrench.

3. An expanding screw anchor comprising a boring member in the form of a disc, a pointed projection formed integral with the underside of said disc, a helix encircling said projection and integral therewith and with said disc, an opening formed in 75 said disc adjacent the upper portion of said helix, expanding plates pivotally secured to the upper surface of said disc, a rod secured in said disc and projection, an expanding member loosely mounted on said rod, means for preventing lateral movement of said expanding member, undercut 80 projections integrally formed with the expanding plates, said under cut projections surrounding the lower portion of the expanding member, a rectangular portion formed integral with the expanding member and above the under cut projections, a wrench for inserting said anchor into the ground, 85 said wrench adapted to be raised and engage the rectangular portion of the expanding member for forcing the expanding plates outward when the anchor is sunk into the ground, an eye having a cylindrical projection screw seated on the upper portion of the rod, said cylindrical portion adapted to 90 steady the upper end of the wrench.

In testimony whereof, I have signed my name to this specification.

JASPER BLACKBURN.
